UNITED STATES PATENT OFFICE.

WALTER J. LLOYD, OF PEABODY, MASSACHUSETTS.

DESIGN FOR A BRUSH-HANDLE.

SPECIFICATION forming part of Design No. 23,749, dated October 30, 1894.

Application filed September 12, 1894. Serial No. 522,847. Term of patent 14 years.

To all whom it may concern:

Be it known that I, WALTER J. LLOYD, a citizen of the United States, residing at Peabody, in the county of Essex and State of Massachusetts, have invented and produced a new and original Design for a Brush-Handle, of which the following is a specification.

Reference is to be had to the accompanying drawing, forming a part of this specification, in which the figure represents a perspective view of a brush handle embodying my new design.

The leading feature of my design consists of the brush handle having the novel configuration and ornamentation as shown. 15

I claim—

The design for a brush handle herein shown and described.

WALTER J. LLOYD.
